UNITED STATES PATENT OFFICE.

JOHN B. PARMELEE, OF DAYTON, OHIO, ASSIGNOR TO THE DAVIS SEWING MACHINE COMPANY, OF DAYTON, OHIO, A CORPORATION OF OHIO.

DESIGN FOR A BICYCLE-FRAME.

41,564.

Specification for Design.

Patented July 11, 1911.

Application filed April 14, 1911. Serial No. 621,171. Term of patent 14 years.

To all whom it may concern:

Be it known that I, JOHN B. PARMELEE, a citizen of the United States, residing at Dayton, in the county of Montgomery and State of Ohio, have invented a new, original, and ornamental Design for Bicycle-Frames, of which the following is a specification, reference being had to the accompanying drawing, forming part thereof.

The figure is a side view of a bicycle frame showing my new design.

I claim:

The ornamental design for a bicycle frame, as shown.

JOHN B. PARMELEE.
